Douglas W. Anderson, Palatine, Ill., assignor to Burgess Vibrocrafter, Inc., Grayslake, Ill., a corporation of Delaware

Filed May 11, 1961, Ser. No. 65,130

Term of patent 14 years

(Cl. D54—14)

FIG. 1 is a side elevational view of an engraving tool or the like embodying my new design;

FIG. 2 is a top plan view thereof;

FIG. 3 is a bottom plan view thereof;

FIG. 4 is an elevational view taken from the left of FIG. 1 thereof, and;

FIG. 5 is an elevational view taken from the right of FIG. 1 thereof.

The essential features of my design reside in the portions shown in full lines.

I claim:

The ornamental design for an engraving tool or the like, substantially as shown and described.
